UNITED STATES PATENT OFFICE.

GUSTAF ALBIN NILSON, OF GLENCOE, ILLINOIS.

PROTECTIVE COVER.

Application filed December 4, 1924. Serial No. 753,904.

My invention relates to protective covers, and more particularly to a protective cover for bath tubs.

Formerly, before built-in bath tubs were used, it was customary to put in the bath tubs after the majority of the other work in the bath room had been completed. Since built-in bath tubs have come into use, however, it has become necessary to install the bath tub before the partitions are in place or the plastering or tile-setting is done in the bath room, as the bath tub is inset into the wall adjacent thereto. It has been found that when a bath tub is installed before this work is done, it is very frequently damaged by the dropping of tools into the same or other heavy objects, or by the shoes of persons standing therein when working on the walls or other portions of the bath room adjacent thereto. It has accordingly been found very desirable to provide some means of protecting the bath tub after it has been installed, to prevent damage thereto.

It is the purpose of my invention to provide a protective covering for the purposes referred to above, comprising a flat body portion that is adapted to cover the entire bath tub including the rim thereof, and to provide means for securing the same in position so that the covering cannot be easily removed. The covering is preferably of such strength that if a mechanic desires to stand on the same to work above the bath tub, the covering will support his weight without damage thereto.

It is a further purpose of the invention to provide means for holding the protective covering member in position on a bath tub that will securely hold the covering in position, and do so without damaging the tub. As bath tubs vary somewhat in size, it is desirable to provide adjustable means engaging the inner face of the tub to prevent transverse movement of the covering relative to the tub, and to further provide means for holding the covering from upward movement relative to the tub.

The covering preferably rests on the top edge portion of the tub, and the means for holding the same from movement upwardly relative to the tub preferably comprises clamping means engaging the tub and means detachably engageable with said clamping

means mounted on the protective covering member. The said means preferably comprises clamping members having upward extensions provided with openings that are adapted to receive bolt-like members that are mounted for axial movement into and out of engagement with the openings in the clamping members.

The clamping means engaging with the inner face of the tub preferably comprises eccentrically-mounted, curved members that are made of a material that will not injure the enamel on the inner face of the bath tub. When the work in the bath room is completed, the cover member, with the bolt-like members and the eccentrically-mounted clamping means, is removed, while the clamps remain in position on the edge of the tub, these being so proportioned and so mounted that the same are imbedded in the plastering or mounted in the back of the tiling or other wall covering that is provided adjacent the edge of the tub, and accordingly are hidden from view. New clamping members must be used for this purpose for each tub that is provided with the protective covering.

Some bath tubs are longer than others, and in order to provide for a covering that will fit these bath tubs, an extension member is provided that is detachably engageable with the main body portion of the protective covering, and which may be of such a size as to properly fit the covering to a tub of any length that it is desired to cover therewith.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings,—

Fig. 1 is a plan view of a bath tub showing my improved covering in position thereon, the adjoining wall portions being shown in horizontal section;

Fig. 2 is a vertical, sectional view of the

bath tub and covering member, showing the bath tub installed;

Fig. 3 is an enlarged detail, sectional view of a portion of the bath tub and protective covering member, showing the means for securing the covering member from upward movement relative to the bath tub;

Fig. 4 is a section taken on the line 4—4 of Fig. 3;

10 Fig. 5 is an enlarged fragmentary view, partly in section and partly in elevation, of the side edge portion of a bath tub, showing the means for holding the covering from transverse movement relative to the tub in 15 adjusted position;

Fig. 6 is a fragmentary section taken substantially on the line 6—6 of Fig. 5;

20 Fig. 7 is a fragmentary vertical, sectional view of a bath tub and my improved covering member, showing a modified construction for holding the covering from vertical movement relative to the tub;

25 Fig. 8 is a similar view showing a further modification of the means for holding the covering from vertical movement relative to the tub;

30 Fig. 9 is a fragmentary plan view of one end of my protective covering, showing an extension member connected therewith;

35 Fig. 10 is a vertical, sectional view thereof; and

40 Fig. 11 is a diagrammatic horizontal, sectional view of a bath room showing a bath tub positioned in the corner thereof, and the 45 arrangement of securing devices for the protective covering for such an installation.

Referring in detail to the drawings, in Figs. 1 and 2 is shown a bath tub 10 that is provided with a laterally extending flange portion 11 around the top edge thereof, said flange portion being imbedded in the plastering 12 provided on the walls 13 when the installation is completed. In using my protective covering, the bath tub 10 is installed 45 before the plastering has been applied to the walls, and the protective covering 14 is put in place thereon. The protective covering, as will be clear from Fig. 1, does not extend to the extreme edge portion of the flanges 11 that are located adjacent the walls 13, but projects slightly beyond the flange portion at the forward edge of the tub, as indicated at 15 in Fig. 1, to protect the corner that is ordinarily exposed at this point. Before putting the covering 14 in place, the clamps 16 are secured to the flanges 11 on the bath tub, preferably at opposite ends thereof. The clamping members 16 are provided with short, laterally extending flanges 17 that are adapted to rest on the upper surface of the edge portion of the tub 10 or on the laterally extending flanges 11 thereof. Said clamping members are further provided with a lower laterally extending flange portion 18 that is screw-threaded to receive the

screw-threaded clamping member 19 that is adapted to be adjusted by turning the same in the member 18 to clamp the flange 17 tightly against the top edge of the tub 10 on the flange portions 11 thereof. The 70 clamping members 16 are further provided with upward extensions 20 with openings 21 therein, with which the bolt-like members 22 are adapted to engage. The bolt-like members 22 are mounted in the bracket members 23 that are secured by any suitable securing devices 24 to the covering member 14. The brackets 23 are provided with upwardly bowed central portions 25 that snugly receive the bolt-like members 22, said bolt-like members 22 fitting snugly in the bowed portions 25 so that the same have to be driven into position in the openings 21. In order to provide means for removing the bolt-like members 22 from the openings 21, the same are provided with notches 26 providing shoulders 27 with which a tool such as a chisel may be engaged to move the bolt-like members 22 to the right in Fig. 3, out of engagement with the members 20. 80

85 The covering member 14 is preferably made of a material made up of a plurality of plies 28 of wood, which are covered on the opposite faces thereof with plies 29 of metal. The metallic plies 29 are preferably 90 bent around the corners or edges of the plies 28, as indicated at 30, to protect the edges of the plies 28 with the metallic covering, said bent-over portions 30 being held in position in any desired manner. 100

105 A plurality of adjustable holding members are provided for holding the cover member 14 from shifting transversely of the bath tub, said members being indicated by the numeral 31 and being preferably curved both eccentrically to the pivot member 32 and to conform to the curvature 33 of the tub 10 between the body portion thereof and the flange portion 11, thus providing a compound curved portion 34 on the member 31 engaging with the curved portion 33 of the tub. The pivot member 32 is preferably made in the form of a bolt-like member, and it will be seen that when the bolt-like member 32 is turned so as to loosen the members 31 that the same can be turned freely to any desired position to adjust the same so that the curved faces 34 thereof will be in snug engagement with the curved faces 33 of the tub 10 on opposite sides thereof. Then the members 32 can be drawn up, tightening the members 31 and holding the same against turning on their pivots. Thus the covering 14 is held firmly from transverse movement relative to the tub 10, and as the members 31 are preferably made of wood or similar material that can be smoothly finished so as to cause no damage to the finish of the inner face of the bath tub, it will be seen that the clamping means, 110 115 120 125 130

while holding the covering member from movement transversely of the tub, will in no way damage the tub.

In the arrangement shown in Figs. 1 and 2, it will be seen that the bracket members 23 and boltlike members 22 are mounted on opposite ends of the tub. When a bath tub is placed in a corner, as shown in Fig. 11, and does not extend from one wall to another, the covering member 14' is preferably rounded off at the end thereof to conform to the rounded end of the tub 10', the holding means 31 being located as in the previously described form, but the bolt-like members 22 and the brackets 23 are preferably located along those edges of the cover 14' that lie adjacent the walls 13'. It will be clear from Figs. 1 to 3, inclusive, that due to the shortness of the flange 17 and the thinness of the member 20, the plastering 12 or other wall covering material will extend over the rim or flange portion 11 of the tub to such an extent as to completely cover the exposed portions of the clamping members 16, which can accordingly be left in position without any objection thereto.

In Fig. 7 the protective cover member 14 is shown as being provided with a different form of securing means for holding the same from movement away from the tub 10, said means comprising a rod member 35 having a hook end 36 adapted to engage under the cross bar 37 provided in the drain 38 of the tub, said member 35 being provided with a threaded end adapted to screw-threadedly receive the nut 36, and a washer 37 being placed between said nut 36 and the cover 14.

Instead of using the clamping member shown in Fig. 7, the cover member 14 may be provided with a hook rod 39 having a hook-shaped end 40 that enters the overflow drain opening 41 in the tub 10, and which is provided with a nut 42 to screw-threadedly engage therewith, and with a washer 43 bearing against the cover 14.

While the cover member described above will fit the ordinary standard-size bath tubs, some bath tubs are made of greater length than the standard size, and in order to fit the cover member to such tubs the extension shown in Figs. 9 and 10 is preferably provided. Said extension comprises a body portion 44 that is made preferably of the same material as the cover member 14 and of the same thickness as said cover member. Said extension 44 is preferably provided with a pair of flanges 45 which are preferably in the form of metallic strips bolted or otherwise secured by the securing members 46 to the edge portion of the member 44 adjoining the end edge of the member 14 to which said member 44 is to be applied. The edge portion 47 of the member 14 preferably fits snugly between the flanges 45, and the ex-

tension 44 is preferably provided with means that is adapted to co-operate with the clamping members 16 comprising a bracket member 48 corresponding in all respects to the bracket member 23, and a bolt-like member 49 corresponding in all respects to the bolt-like member 22, and operating in the same way to hold the cover member from movement upward relatively to the bath tub. It will be evident that the extension 44, due to the provision of the flanges 45, will not be capable of vertical movement relative to the member 14, and accordingly the securing means against vertical movement at the opposite end of the member 14 and the member 49 will co-operate to hold the cover member 14 with its extension from removal from the tub 10.

Having thus described my invention what I desire to claim and secure by United States Letters Patent is:

1. A cover of the character described comprising a substantially flat body portion, a plurality of clamping members adjustably mounted thereon to project from one face thereof and a plurality of holding members mounted on the other face thereof.

2. A cover of the character described comprising a substantially flat body portion and a plurality of nonmetallic clamping members mounted eccentrically thereon to project from one face thereof.

3. A cover of the character described comprising a substantially flat body portion and a plurality of clamping members having compoundly curved clamping faces concave in one direction mounted eccentrically thereon to project from one face thereof.

4. A cover of the character described comprising a substantially flat body portion and a plurality of nonmetallic clamping members having curved clamping faces mounted eccentrically thereon to project from one face thereof.

5. A cover of the character described comprising a substantially flat body portion, a plurality of clamping members adjustably mounted thereon to project from one face thereof and a plurality of axially movable holding members on the opposite face of said body portion.

6. The combination with a bathtub of a protective covering therefor comprising a substantially flat body portion engaging the top edge of said tub, means on one side of said body portion engaging the inner face of said tub to hold said covering from movement transversely of said tub and means on the other side of said body portion for holding said covering from upward movement relative to said tub.

7. The combination with a bathtub of a protective covering therefor comprising a substantially flat body portion engaging the

- 4 top edge of said tub, adjustable means on one side of said body portion engaging the inner face of said tub to hold said covering from movement transversely of said tub and means on the other side of said body portion for holding said covering from upward movement relative to said tub.
8. The combination with a bathtub of a protective covering therefor comprising a substantially flat body portion engaging the top edge of said tub, adjustable clamping means on one side of said body portion engaging the inner face of said tub to hold said covering from movement transversely of said tub and means on the other side of said body portion for holding said covering from upward movement relative to said tub.
9. The combination with a bathtub of a protective covering therefor comprising a substantially flat body portion engaging the top edge of said tub, adjustable clamping means having curved faces engaging the inner face of said tub to hold said covering from movement transversely of said tub and means for holding said covering from upward movement relative to said tub.
10. The combination with a bathtub of a protective covering therefor comprising a substantially flat body portion engaging the top edge of said tub, means engaging the inner face of said tub to hold said covering from movement transversely of said tub and means for holding said covering from upward movement relative to said tub, comprising clamping means engaging said tub and means on said body portion detachably engageable therewith.
11. The combination with a bathtub of a protective covering therefor comprising a substantially flat body portion engaging the top edge of said tub, means engaging the inner face of said tub to hold said covering from movement transversely of said tub and means for holding said covering from upward movement relative to said tub, comprising clamping members engaging said tub and having openings therein and means on the outer face of said body portion projectable into said openings.
12. The combination with a bathtub of a protective covering therefor comprising a substantially flat body portion resting on the top edge of said tub, means engaging the inner face of said tub to hold said covering from movement transversely of said tub and means for holding said covering from upward movement relative to said tub, comprising clamping members engaging said tub and having openings therein and means on said body portion projectable into said openings by axial sliding movement thereof.
13. The combination with a bathtub of a protective covering therefor comprising a substantially flat rigid body portion resting on the top edge of said tub, means engaging the inner face of said tub to hold said covering from movement transversely of said tub, a rigid extension engageable with said body portion and means for holding said covering from upward movement relative to said tub.
14. The combination with a bathtub of a protective covering therefor comprising a substantially flat rigid body portion resting on the top edge of said tub, means engaging the inner face of said tub to hold said covering from movement transversely of said tub, a rigid extension engageable with said body portion and means for holding said covering from upward movement relative to said tub comprising clamping means engaging said tub and means on said body portion and extension detachably engageable therewith.
15. The combination with a bathtub of a protective covering therefor comprising a substantially flat rigid body portion resting on the top edge of said tub, means engaging the inner face of said tub to hold said covering from movement transversely of said tub, a rigid extension engageable with said body portion, the abutting edges of said body portion and extension interfitting, and means for holding said covering from upward movement relative to said tub.
16. The combination with a bathtub of a protective covering therefor comprising a substantially flat body portion resting on the top edge of said tub, means engaging the inner face of said tub to hold said covering from movement transversely of said tub, a rigid extension engageable with said body portion, the abutting edges of said body portion and extension interfitting, and means for holding said covering from upward movement relative to said tub comprising clamping means engaging said tub and means on said body portion and extension detachably engageable therewith.
17. A cover of the character described comprising a substantially flat body portion, a plurality of clamping members mounted thereon to project from one face thereof and a plurality of holding members mounted on the other face thereof, said holding members being mounted for projection beyond the edge of said body portion.
18. The combination with a bathtub, of a protective covering therefor comprising a substantially flat body portion engaging the top edge of said tub, means engaging the inner face of said tub to hold said covering from movement transversely of said tub and means for holding said covering from upward movement relative to said tub, certain of the edges of said body portion ending short of the outer top edges of said tub and said holding means being projectable beyond said edges of said body portion.
19. The combination with a bathtub, of a protective covering therefor comprising a

- substantially flat body portion engaging the top edge of said tub, means engaging the inner face of said tub to hold said covering from movement transversely of said tub and means for holding said covering from upward movement relative to said tub, certain of the edges of said body portion ending short of the outer top edges of said tub and said holding means comprising members ¹⁰ 10 gaging the extreme outer edge portions of said tub and members on said body portion projectable beyond the edges thereof into engagement with said members on said tub.
20. The combination with a bathtub having a rim around the top edge thereof, of a rigid cover member resting on said rim, said cover member having an edge on one side thereof extending laterally beyond the outer
- edge of said rim and having edges on a plurality of sides thereof terminating short ²⁰ of the outer edge of said rim.
21. The combination with a bathtub having a rim around the top edge thereof, of a rigid cover member resting on said rim, said cover member having an edge on one ²⁵ side thereof extending laterally beyond the outer edge of said rim and having edges on a plurality of sides thereof terminating short of the outer edge of said rim, and means on said cover for securing the same on said bathtub.

In witness whereof, I hereunto subscribe my name this 1st day of December, A. D. 1924.

GUSTAF ALBIN NILSON.
